UNITED STATES PATENT OFFICE.

WILLIAM ESTY, OF LACONIA, NEW HAMPSHIRE.

KNITTING-MACHINE.

SPECIFICATION forming part of Letters Patent No. 371,567, dated October 18, 1887.

Application filed July 20, 1887. Serial No. 244,808. (No model.)

To all whom it may concern:

Be it known that I, WILLIAM ESTY, of Laconia, in the county of Belknap and State of New Hampshire, have invented certain new and useful Improvements in Knitting-Machines, of which the following, taken in connection with the accompanying drawings, is a specification.

My invention relates to knitting-machines; and it consists, first, in the combination, with the needles of a straight-knitting machine and the needle-operating cam-bar, of a series of stationary hooked sinkers, cams constructed and arranged to first depress and then immediately raise the hooked ends of the needles to place the fabric beneath the hooks of the sinkers as said needles are moved endwise by their actuating-cams to form the loops, and means for actuating the lowering and raising cams from the needle cam-bar, with a certain amount of play or lost motion to cause the said cams to properly "follow" the needle-actuating cams in the actuation of the needles, all so constructed and arranged that the least possible number of needles will be depressed at the same time, whereby the work will be more firmly held than when a greater number of needles are depressed and held down a longer time.

My invention consists, secondly, in an improved and simple means for holding the sinkers and securing them firmly in place, and whereby provision is made for the convenient and ready removal of any or all of the sinkers, and for the adjustment of the latter relatively to the needles.

Figure 1 of the drawings is a plan of so much of a machine having my invention applied thereto as is necessary for the proper understanding of the invention. Fig. 2 is a sectional elevation of the same, the cutting-plane being on line *y* *y* on Fig. 3. Fig. 3 is a transverse section on line *x* *x* on Figs. 1 and 2, looking toward the right of said figures. Fig. 4 is an elevation of the inner side of the sinker-plate. Fig. 5 is an elevation of one of the sliding-block bearings for supporting the sinker-locking-slide. Fig. 6 is a section through a portion of the parts on line *z* *z* on Fig. 2. Fig. 7 is an elevation of one of the sinkers detached from the machine. Figs. 8 and 9 are respectively an elevation and vertical section

illustrating a modification of the cam-bars for throwing down the hooked ends of the needles, and Fig. 10 is an elevation of a portion of the ends of the needle-bending cam-bars opposite to that shown in Figs. 1 and 2.

A is the needle-bed, which may be of any usual or suitable construction, save that the transverse grooves therein for the reception of the needles are made somewhat deeper than usual to permit of the depression of the hooked ends of the needles, in the manner which will be hereinafter described.

B is the needle cam-bar fitted to slide on the guide-bars *D* and *D'*, and having secured thereto the needle-actuating cams *G*, said cam-bar having a reciprocating movement imparted thereto through the medium of the rod *B'*, in any usual and desired manner. To the cam-bar *B* is attached the yarn guide or carrier *C*.

E designates the needles, and *F* a cap placed at the front of the needle-bed and serving to keep the forward ends of the needles from rising out of the grooves therefor in the needle-bed. This cap is secured by screws *F'* to the needle-bed *A*, so as to provide for its ready removal. The front of the needle-bed is formed with or has attached thereto a rearwardly-inclined downward extension, *H*, the forward face of which is formed with a ledge, *H'*, and groove *H''*, as shown. To the front of the ledge *H'* a sinker-plate, *J*, is removably secured by means of screws *J'*, this plate being formed with rearward projections *J''*, *J'''*, and *J''''*, (see Fig. 4,) the lower edges of which rest upon the top of the ledge *H'*, as shown in Fig.

3. The central projection, *J''*, of the sinker-plate *J* is grooved, as shown in Fig. 4, for the reception of the sinkers *I*, the blades of which are notched, as at *b*, for the reception of a tongue or rib, *c*, on a slide, *H''*, which is fitted within the groove *H''*, but so as to be capable of readily being adjusted vertically to enable the position of the hooks *d* of the sinkers *I* to be properly adjusted relatively to the needles.

The slide *H''* passes at its ends through blocks or boxes *H''* *H'''*, fitted to move vertically between the projections *J''* and *J''''* of the plate *J* and in corresponding bearings cut in the ledge *H'*, and are secured to the extension *H* by screws *e*, passing through slots *e'* in the said extension. By loosening the screws *e* the boxes *H''* *H'''* and slide *H''*, and with the latter

the sinkers I, may be moved up or down at will, and then secured in the desired position by again tightening the screws e. The slide H³ moves freely through the boxes H⁴ H⁴, and 5 the tongue or rib c thereon is formed with a tapered end, as shown at f in Fig. 2. By withdrawing the slide endwise the tongue or rib c will be withdrawn from the notches of the sinkers, and any or all of the latter may then 10 be withdrawn from the grooves therefor in the sinker-plate J. The tapered end of the tongue or rib c enables it to pass without obstruction through the notches of the sinkers.

Upon the upper side of the needle-bed, near 15 its front edge, is formed a groove or bearing extending longitudinally thereof, in which is fitted, so as to be movable endwise therein, a bar, N, in position to support the hooked ends of the needles, said bar being provided with 20 the slot g at its end, with which a pin, g', set in the end of the arm N', secured upon the rod B', engages to move said bar with the needle cam-bar during the greater part of its reciprocation, and above the ends of the needles, 25 within a groove cut in the under side of the cap E, slides a bar, O. These bars N and O are hinged together at h, as shown in Figs. 1 and 2, and at the opposite end the bar O is provided with a pin or projection, R, sufficient 30 in length to hold it above bar N a distance about equal to the thickness of the needles. The bar N is formed on its upper surface with a curved depression at i, and above this depression, on the bar O, is formed a correspondingly-curved cam or projection, i', all 35 as shown in Fig. 2.

The construction of the cam for depressing and raising the hooked ends of the needles in two parts, hinged together at one end and 40 kept the proper distance apart at their other ends by a stop-pin or lug, as described, is for the purpose of facilitating the removal of the needles, as when the needle-operating cam-bar B and the cap F are removed the bar O can 45 be readily raised or moved about its pivot h, so that any or all of the needles may be removed, and the depression in the bar N and the projection from the bar O are so formed that as said bars reciprocate the needles are 50 depressed by said projection from the bar O a certain fixed distance; but as quick as a needle has reached the lowest point to which it is to be depressed the upward curve of the depression in the bar N begins to act upon 55 said needle to raise it to its former level, whereby not more than one or two needles at most are depressed to their lowest positions at the same time, and the greatest possible number of needles are maintained at all times in 60 their normal position as to the elevation of their hooked ends, thereby much more firmly holding the work than when a large number of needles are depressed at the same time.

At their forward ends the needles rest upon 65 and are sustained by the upper surface of the bar N, being thereby held above the bottoms of the grooves in the needle-bed.

The tongue or rib c on slide H³, while in engagement with the notches of the sinkers, holds the latter firmly in place; but by with- 70 drawing the said slide endwise the sinkers are freed and may readily be removed.

The sinkers are formed as shown, with inclined faces or portions j, against which the loops are drawn as the needles are moved 75 back by the cams G, these faces being placed at a right angle to the line of movement of the needles.

The slot g and pin g', for actuating the bars N O from the cam-bar B and providing for 80 lost motion, may be replaced by any known and equivalent devices which will secure the same result. The amount of play or lost motion is to be such that in whichever direction the cam-bar B is moved the middle point of 85 the cam projection i' and depression i will lie on a line drawn across the needle-bed at right angles to its length and passing through one of the final drawing-points g² of the cams G. By this means I insure the complete depression 90 of the hooked end of the needle with the loop thereon below the hooks on the sinkers I just as the drawing-point g² is acting to give the final rearward movement to the needle to draw in and close up the newly-formed loop 95 or stitch.

In Figs. 1 and 2 the parts are in the relative position in which they lie while the cams G and bars N and O are moving toward the left-hand side of the machine, the depression i and 100 projection i' being in line with the following cam g².

In operation, as the needles E are successively projected and retracted by the cams G and the yarn is laid in the hooks of the needles by the carrier or guide C, the cam or projection i' acts upon the rearwardly-moving needles and depresses the hooked ends thereof with the fabric thereon below the hooks of the sinkers. Then, after the stitches have been 110 completed by the action of the following drawing-point g² of the cams G, the hooked ends of the needles are caused to rise as they move up the side of the depression i in bar N, so as to carry the yarn of the newly-formed course of 115 loops under and within the hooks of the sinkers.

I may replace the cam or projection i' of the bar O (shown in Fig. 2) by a roller, i³, pivoted to the said bar, as shown in Figs. 8 120 and 9.

My means of securing the sinkers in place enables me to wholly dispense with the use of solder.

The construction herein shown enables me 125 to avoid having to raise and lower the hooked sinkers to cause them to properly engage with the fabric being knitted, as in previous machines. There is no danger of the stationary sinkers improperly engaging or interfering 130 with the yarn as it is being fed to the needles.

Having described my invention, I claim—
1. The combination, with the needles and the needle-operating cam-bar, of a series of

stationary hooked sinkers, cams for lowering and raising the hooked ends of the needles as they are moved by the needle-operating cams to form the loops, said cams being constructed 5 and arranged to depress said needles a given distance and immediately raise them again without holding them in said depressed position, and means having provision for lost motion for operating the said needle lowering 10 and raising cams from the needle cam-bar, substantially as described.

2. The combination, with the needles and the needle-operating cam-bar, of a series of stationary hooked sinkers, the bars N and O, 15 pivoted together, as set forth, the pin or projection R, and means having provisions for lost motion for operating the said bars from the needle cam-bar, substantially as described.

3. The combination, with a sustaining-bar, 20 a sinker-plate grooved for the reception of sinkers, and a series of sinkers fitted to the grooves of the sinker-plate, and having shoulders or holding-surfaces formed upon their shanks, of a locking-bar provided with shoul-

ders or holding-surfaces constructed and arranged to engage with the shoulders on all of said sinkers to lock them in position and adapted to be withdrawn to permit the removal of one or all of said sinkers. 25

4. The combination, with a sustaining-bar, 30 the grooved sinker-plate, and the sinkers provided with locking-shoulders, of a locking-bar provided with shoulders or holding-surfaces constructed and arranged to engage with the shoulders on all of said sinkers, and lock 35 them all at the same height, and means for adjusting said bar in the direction of the length of said sinkers to regulate the height of said sinkers relative to the needles, substantially as described. 40

In testimony whereof I have signed my name to this specification, in the presence of two subscribing witnesses, on this 14th day of July, A. D. 1887.

WILLIAM ESTY.
